UNITED STATES PATENT OFFICE.

MATHYS VAN DEN HEUVEL AND PETRUS MARTINUS DIKS, OF UDEN, NETHERLANDS.

STRAW-CASE-MAKING MACHINE.

1,248,209.

Specification of Letters Patent. Patented Nov. 27, 1917.

Application filed June 2, 1915. Serial No. 31,779.

To all whom it may concern:

Be it known that we, MATHYS VAN DEN HEUVEL and PETRUS MARTINUS DIKS, subjects of the Queen of the Netherlands, residing at Uden, Province of Noord Brabant, Netherlands, have invented certain new and useful Improvements in Straw-Case-Making Machines, of which the following is a specification.

10 The invention consists in improvements in continuous folding and feed devices for straw-case-making machines.

Machines hitherto used for the manufacture of straw cases, usually have a single 15 folding device arranged next to the straw-case-making machine proper, the said device folding the straw to be treated to the dimension required, whereupon it is introduced by hand into the straw-case-making machine 20 in which it is subjected to further treatment. This process is, however, complicated and takes up a great deal of time, as the attendant has first to give attention to the folding of the straw in the folding device, 25 and afterward to the introduction of the straw into the machine in correct position and at the proper point.

In other known machines, the folding and the making of the straw into a case are both 30 effected in the same device. The straw which is pushed by hand into a so-called "filling frame," is pushed by the said filling frame, which reciprocates in a horizontal plane, into that portion of the machine 35 where it is converted into a straw case. The empty filling frame thereupon returns to its initial position, is again filled with straw, whereupon the same process is repeated.

The return to the original position in the 40 devices at present used, is effected either under the action of a weight, or by means of an endless chain or the like. It is obvious that this reciprocation of the filling frame in the machine is unfavorable to a large 45 output of the device, as during the time occupied by the travel, the machine could be filled again, and the attendant is forced to wait until the filling frame has returned to the original position, before straw can 50 again be introduced into the machine.

In the device according to this invention the capacity of the straw-case-making machine is increased in a simple manner. The

filling frame, in which the straw is also folded before treatment merely feeds the 55 folded straw to the machine, instead of participating in the movement which the straw executes in the machine. After the filling of the frame, it is vertically lowered to a slight extent, which results in the straw 60 contained in the frame, being seized by the teeth or points of a conveyer chain and conveyed to the machine. As soon as the frame has been thus emptied, it is automatically returned to the highest position and 65 can be charged again, whereupon it again executes a limited downward travel, and its contents are seized by the conveyer chain. In this way, a much larger number of 70 charges can be supplied in a given period of time, so that the output of the machine is increased.

A construction of the device according to this invention is illustrated in the accompanying drawings in which—

75 Figure 1 is a front elevation, partly in section, of a straw-case-making machine provided with a feed device according to the invention. Only the most important parts of the straw-case-making machine proper 80 are shown.

Fig. 2 is a plan of Fig. 1.

Fig. 3 is a side elevation of the same device.

Fig. 4 is a transverse sectional view of 85 the frame above referred to, together with the driving device for the straw to be treated.

Fig. 5 is a longitudinal detail sectional view of the frame shown in Fig. 4, together with accessories, at the moment when 90 it is in its lowest position in which the chain seizes the straw and brings it into the machine.

Fig. 6 is a view similar to that shown in 95 Fig. 5, the frame being shown in its highest position in which therefore it can be filled again.

Fig. 7 is a plan of the device shown in Figs. 5 and 6, the cover of the frame being 100 shown open.

The straw-case-making machine shown in Fig. 1 comprises a frame 1 to which is secured the mechanism converting the straw supplied into cases and consisting chiefly of 105 a cylinder 2, about which the straws are

5 moved parallel to its axis, while needles 4 vertically adjustable through the openings 3 of the hollow cylinder, coöperate in the known manner with a slide 5 longitudinally movable in the cylinder parallel to its axis; wires from the supply spools, introduced at one end into the cylinder 2, are carried by the said needles 4.

10 The needles are arranged on the upper surface of a frame 6 vertically movable under the cylinder in vertical guides and driven upward from the main driving spindle of the device, while the downward movement takes place under the action of 15 gravity.

The direction of movement of the straw to be treated is normal to the axis of the cylinder, the straws lying parallel to the axis of the cylinder.

20 From the feed device hereinafter more fully described, the straws pass over a horizontal guide surface 7 to the cylinder. The straw first passes under the cylinder 2 whereupon it passes through several circular 25 brackets 8 surrounding the cylinder at the desired distance and forcing the straw to travel around the cylinder 2, after it has been sewn together to form a kind of matting by the needles passing through the openings 3 at the lower surface of the cylinder.

30 In that way, the beginning of each matting formed in the manner described, is twisted with its end in such a manner that a cylinder-shaped case is produced, which, after it 35 has been moved laterally, away from the cylinder, is tied at one end and is then ready for use. In order to press the straw firmly against the cylinder during its movement arms 9 are used which are pivoted or hinged

40 to a spindle 10 and provided with a resilient part or holder 11. The part or holder 11 is provided with teeth 12 used for pressing the straw against the cylinder. Moreover, the upper surface of the frame 6, to which 45 the needles 4 are secured is provided with drivers or lower coöperating holders 13 co-operating with the arms 9 and also pressing more firmly the straw which is around the cylinder. The supply of straw to the machine is effected by means of a number of

50 endless chains 14 arranged side by side and provided on their upper surface with teeth 15, each of the said chains passing over two chain wheels 16 and 17 keyed to spindles 18

55 and 19 rotatable in bearings 20, 20 or 21, 21 secured to the frame 1. The chain wheels are driven from the driving shaft 22 arranged in the lower part of the frame. The upper portion of the chains is guided be-

60 tween the chain wheels in U-shaped guides 23, the sides of which are so high that only the points of the teeth project above them and seize the straw. The upper surface of the chain is situated in the plane of the 65 guide surface 7 for the straw. According to

the invention, between the two chain wheel spindles 18 and 19 is arranged a vertically adjustable filling frame 24 consisting of an open frame for affording passage to the conveyer chain 14. The said frame can be 70 driven in any desired manner from the main driving spindle 22 or from one of the spindles 18 and 19. In the construction shown in the drawing, the frame is moved by a system of levers hereinafter more fully 75 described.

The working of the filling frame itself is as follows:—

The filling is effected by hand, at the moment when the frame is in its highest 80 position. In the open position of the cover 25 rotatable about the hinges 41 (Fig. 7), the straws are laid on the filling frame parallel to the axis of the cylinder 2 and so that the said frame, as well as the opened 85 cover, is completely covered. Thereupon in the center, transversely of the straw and over it, is placed a so-called folding knife resting against a fixed blade 26 and the cover is closed by means of a handle 42 provided 90 for the purpose, whereupon the folding knife can be withdrawn from the machine in the direction normal to the spindle 30. The folding knife referred to is not shown in the drawings, the said device being well 95 known in this art. It consists of a simple bar knife preferably having the form of a ruler and is placed on the stretched strands of straw, the straw being folded about the knife by closing the cover 2. After this latter operation ensues, the knife which rests against the blade 26 is withdrawn from the machine by hand.

All the strands of straw will therefore be folded upon themselves, the fold being at 105 the side which subsequently forms the opening of the case. The filling frame thereupon descends automatically to such an extent that the points 15 on the links of the chain 14, which at that moment are situated under 110 the frame, engage with the straw and carry the contents of the filling frame to the cylinder 2, where it is subjected to the action just described. As soon as the contents are completely removed from the frame, the latter 115 automatically returns to its highest position and thus out of reach of the chains 14, so that a new filling can take place.

The attendant must keep time with the machine, as the filling of the frame must be 120 completed before the beginning of the downward movement, as the frame can no longer be filled in the lower position. The advantages attained by means of this device, have been described above.

125 The vertical reciprocation of the filling frame in the construction shown in the drawing, is insured in the following manner: The bottom of the filling frame is provided at the four corners with downwardly ex- 130

tending arms 27. The four lower ends of the arms 27 are hinged to levers 28 and 29. The levers 28 and 29 rotate about the same spindle 30 and make such an oscillating movement that the filling frame 24 is vertically reciprocated. The pivot points of the arms 27 on the levers 28 or 29 are given the play required for this movement. The levers 28 which are one-armed, are pivoted to the spindle 30. The levers 29, which have intermediate angular deflections, are pivoted at one end to the arms 27 at the right hand side of the filling frame. At the end shown on the left in the drawing, all the levers 15 are provided with tappets 31 and 32 coöperating with cam disks 33 provided on the chain wheel spindle 18. These cam disks drive the four corners of the frame continuously up and down by means of the 20 levers 28 and 29.

In the constructions shown in Figs. 5-7, there are only two cam disks on the spindle, and both levers 28 are keyed to the spindle 30 rotatable in the machine frame, while 25 the levers 29 are connected to a sleeve rotatable on the spindle 30.

The cam disks are of such a shape that the downward movement of the filling frame takes place suddenly, while the upward 30 movement is gradual.

The conveyer chain comprises, as usual, a series of links provided with teeth 35, and a series of links without teeth, as the corresponding part of the chain is not required for conveying the straw.

In the device according to this invention there is between each series a so-called clamping member 36 provided with teeth 37 having curved forward edges, the said teeth 40 37 being in planes at right angles to the members 36. The forward curved edges of the teeth 37 provide for gathering up and pressing the straw toward the cylinder while the said cylinder is coöperating with the 45 straw, but preventing the straw from being dragged away in view of the curved edges which permit the straw to readily pass over the teeth as the conveyer chain continues to move. In other words, the teeth 37 with 50 their front curved edges provide means for gathering up the straw and pushing it toward the cylinder to insure the formation of the cases as compact as possible.

The device is constructed so that, at the 55 moment when the filling frame is suddenly lowered, one of the toothed parts of the chain is situated under the filling frame, so that the straw is pressed down to these teeth and withdrawn by the chain from the filling 60 frame 24 or pushed forward. As soon as the straw leaves the filling frame, it is depressed by means of spring blades 40 provided on guides 39, so that the straw arrives under the cylinder 2 in the form of a 65 compact mat. The guides 39 are arranged

at definite distances apart on a bracket 38 extending throughout the whole width of the guide surface for the straw.

The use of the improved folding and feeding device according to this invention enables the work to be done much more quickly than by the devices hitherto used for the purpose, as the filling frame has to execute merely a limited vertical reciprocation for the purpose of delivering the straw to a 70 conveyer chain, whereupon the filling frame is at once filled again.

What we claim as our invention and desire to secure by Letters Patent is:—

1. In a folding and feeding device for straw-case-making machines, the combination with a filling frame adapted to reciprocate vertically, of toothed conveying chains beneath said frame, a spindle beneath the frame, a set of single-armed levers connected 80 to two corners of the frame and pivoted to the spindle, a set of angularly deflected levers connected to the other two corners of the frame and also pivoted to the spindle, and rotating cam disks engaging the free 85 ends of said levers whereby the frame is reciprocated vertically parallel to itself.

2. In a folding and feeding device for straw-case-making machines, the combination with a filling frame, of conveyer chains 90 having driving teeth and arranged beneath said frame, spindles and chain-wheels carrying said chains, a spindle beneath the frame, levers pivoted to said spindle and connected to the frame, and cam-disks secured to one 95 of the chain carrying spindles and adapted to engage the free ends of said levers to reciprocate the frame vertically.

3. In a device of the class specified, the combination with a rotatable cylinder and a 100 filling frame, of means for reciprocating the said filling frame vertically and imparting thereto a comparatively rapid lowering movement and a slower upward movement, and conveyer chains movable under the said 105 filling frame and cylinder and comprising groups of links provided with pointed teeth, links in rear of the links having the pointed teeth and provided with rearwardly inclined teeth for giving the straw charges as fed to 110 the cylinder an equal thickness and requisite fullness, and groups of links without teeth between the groups having pointed teeth and those having rearwardly inclined teeth.

4. In a straw case making machine, a case 120 former, guide means spaced from said former and coöperating therewith in shaping the case, and a filling frame for feeding straw between said former and guide means and provided with devices for reciprocating 125 the same at intervals.

5. In a straw case making machine, a case former, guide means spaced from said former and coöperating therewith in shaping the case, stitching mechanism for bind- 130

ing the straw in sheet form as the latter is fed to the former, and a filling frame for feeding straw between the said former and guide means and provided with devices for regularly reciprocating the same at intervals.

In testimony whereof we have hereunto

set our hands in presence of two subscribing witnesses.

MATHYS VAN DEN HEUVEL.
PETRUS MARTINUS DIKS.
